UNITED STATES PATENT OFFICE.

ALBERT L. WOLFSON AND ALFRED N. HAMMERSTON, OF NEW YORK, N. Y.

TURBINE-BLOWER.

1,050,505.

Specification of Letters Patent. Patented Jan. 14, 1913.

Application filed April 24, 1912. Serial No. 692,935.

To all whom it may concern:

Be it known that we, ALBERT L. WOLFSON, a citizen of the United States, and ALFRED N. HAMMERSTON, a subject of the Emperor 5 of Germany, residing at New York city, county of New York, State of New York, have invented a new and useful Improvement in Turbine-Blowers, of which the following is a specification.

10 This invention relates to turbine blowers, that is, fans driven by steam turbines, the rotor of the turbine and the fan being combined as a unit.

The object of the invention is to increase 15 the efficiency of such blowers, and particularly to enable them to run economically at the lower speeds.

In general, the object is to improve the construction of this kind of apparatus in 20 various particulars making for simplicity and cheapness of construction, efficiency in operation, and convenience of control.

The invention, in its preferred form, will 25 now be described, reference being had to the accompanying drawings, wherein:

Figure 1 is a front view of the apparatus with the casing; Fig. 2 is a longitudinal section of the same with the casing; Fig. 3 is a back view of the rotor; Fig. 4 is a 30 fragmentary front elevation of the spider and the stationary plate or casting formed with or carried thereby and provided with the annular steam chest and nozzles; Fig. 5 is an enlarged section on the line 5—5 of Fig. 4; and Fig. 6 is a section on a smaller scale on the line 6—6 of Fig. 4.

The numeral 1 designates a suitable cylindrical casing or open ended tube, and 2 is a spider having an outer ring 3 which is 40 bolted or otherwise removably secured to the rear or outer end of the casing. The spider carries a forwardly-projecting axial shaft 4 which is preferably fixed stationarily in a hub portion 5, as by set screws 6. 45 On this stationary shaft in front of the spider support is mounted the rotor, designated as a whole by the numeral 7. The said rotor or rotary unit comprises a propeller fan composed of a series of blades 8 50 occupying its outer portion, and a turbine part 9 located concentrically inside of the fan. This turbine part is shown composed of a series of buckets 10 mounted in an annular recess 11 formed in the part 9 of the 55 rotary unit, the said recess being open at the back to nozzles 12. These nozzles are

carried by the spider 2 and are supplied by an annular steam chest 13 also carried by the spider support. The steam chest is preferably formed inside a stationary back plate 60 or casting 14 carried by the spider at and in front of its central portion. The annular steam chest is supplied by a steam pipe, which may be threaded into a hollow boss 16 projecting from the back of this plate. 65 The annular steam chest preferably extends all the way around the axis of the device, in a complete circle.

The nozzles 12, which are inclined forwardly, are preferably located partly or entirely in an annular groove or recess 17 at the front of the back plate 14, which groove is preferably concentric with and outside of the steam chest 13. They are shown connected with the steam chest by outwardly-extending branch passages 18, formed in 70 ribs 19, which cross the said recess 17. These ribs have suitably inclined sides, so that the nozzles 12 may be screwed into them with their lock nuts 20 abutting 75 against these sides. The nozzles are thus disposed at an angle to the branch passages 18, the outer ends of which may be closed by screw plugs 21.

Means are provided for shutting off any 80 one or more of the nozzles independently of the others. To this end individual valves 22 are provided, one for each nozzle. Thus, to reduce the speed of the blower, one or 85 more of the nozzles are cut off entirely, 90 instead of reducing the flow through all the nozzles by manipulating an adjustable valve controlling the supply to the steam chest, thereby reducing efficiency by lowering the steam pressure. In this way, an 95 economical control may be substituted for a wasteful one, but in an apparatus of this character another problem presents itself, arising from the fact that a turbine blower operates on a very small amount of steam, 100 and hence its steam chest, for proper efficiency, must be of restricted cross-section. In recognition of this condition the individual valves 22 are so arranged that they 105 do not enter or obstruct the steam chest. Preferably they co-operate with the branch 110 passages 18 and seat against the rear ends of the nozzle openings 15. In the particular construction shown the valve stems are disposed perpendicular to these passages 18 and entirely clear of the steam chest, being threaded into openings in the plate 14 and

having their operating ends or handles projecting in rear thereof, where they may be operated with convenience.

The rotary unit 7 has a hub portion 23 turning about the shaft 4, and a solid web portion 24 connecting this hub with the bucket casing part 9 and thereby blanking the fluid region at the center of the fan. The fan blades 8 are secured or fixed at their inner ends to the bucket casing part 9. The buckets 10 are preferably secured between rings 26, 27, and the annular structure thus formed is suitably secured in the annular recess 11. Preferably the forward part of this recess is unoccupied, and constitutes an exhaust steam chamber 28.

In accordance with the invention a plurality of exhaust ports 29 are provided, the same being spaced away from the axis of the rotor and located close to the fan blades 8, so that the exhaust steam issues freely from the exhaust ports and is promptly acted upon by the fan blades and forced along with the air longitudinally of the casing 1. As shown, the ports 29 are distributed in circular series and are located directly in front of the series of buckets 10, being formed through the front wall of the recess 11.

The shaft 4 is provided at its front end with an integral enlarged head 30, having a rounded face. A bushing or sleeve 31 is mounted rotatably on the shaft between this head and the stationary hub portion 5. The outer part of the bore of this bushing is enlarged, so as to receive the head 30, and a disk or thrust member 32 is screwed into the outer end of this bore enlargement and keyed. The head is thus inclosed in a two-part bearing, the end wall of which bears against the rounded face of the head. The bushing 31 is suitably and removably secured in the hub portion 23 of the rotor. Preferably the outer wall of the bushing 31 and the inner wall of the hub portion 23 are screw threaded, so that the rotor is screwed on over the bushing and its end bearing member 32 and keyed as by a screw 60, after the latter have been assembled on the shaft, and preferably before the shaft is secured in the hub 5 of the spider 2. The rear end of the bushing may be provided with spanner openings to facilitate the screwing of the rotor and bushing together. The outer side of the end thrust member 32 may likewise be provided with spanner holes, to enable it to be screwed into the bushing. Thus, in assembling, the bushing 31 and disk 32 are first screwed or otherwise secured together on the shaft, then the rotor is screwed onto this bearing structure, and finally the shaft is secured by the set screws 6 in the hub of the spider. The set screws 6 enable the shaft with the rotor to be adjusted axially 65 relatively to the spider support and the noz-

zles carried thereby. The front of this hub portion 23 may be closed by an integral end wall, since the rotary unit 7 is merely put on over the two-part bearing 31, 32 and secured thereto. In this way a very simple and efficient bearing structure is afforded and made dirt-proof. The shaft 4 with the bearing 31, 32 thereon may be removed entire if trouble arise, and be replaced by another shaft and bearing, without occasioning any disassembling of the rotor.

The shaft 5 is preferably hollow, to constitute an oil duct and has oil channels 35 extending through its wall. The rear end of the bore of the shaft may be threaded to receive an oil pipe leading from an oil cup (not shown).

The operation of the apparatus will be obvious from the foregoing.

What is claimed as new is:

1. In a turbine blower, the combination of a support, an annular steam chest of restricted cross-sectional area carried thereby, nozzle branches with nozzles leading from said annular steam chest, individual cut-off means external to said annular steam chest controlling said nozzle branches and a rotary unit comprising a fan with buckets arranged to be impinged by the jets from said nozzles.

2. In a turbine blower, the combination of a supporting spider carrying a stationary plate at the center thereof, said stationary plate having an annular steam chest formed therein, nozzles carried by the stationary plate at the front thereof, individual cut-off means external to said annular steam chest controlling said nozzles, a shaft carried by the spider, and a rotor mounted on said shaft and including an annular series of buckets arranged to be impinged by the jets from said nozzles and fan blades arranged concentrically outside of said series of buckets.

3. In a turbine blower, the combination of a supporting spider carrying a stationary plate at the center thereof, said stationary plate having an annular steam chest formed therein, an annular groove at the front concentrically outside of the steam chest, and cross ribs in said groove containing branch passages from the steam chest, nozzles attached to said ribs, and a rotor in front of the stationary plate comprising concentrically arranged fan blades and buckets, the latter constituting the inner series and arranged to be impinged by the jets from said nozzles.

4. In a turbine blower, the combination of a cylindrical casing, a spider removably attached thereto, an annular steam chest carried by said spider, nozzles connected with the steam chest, individual cut-off means external to said annular steam chest controlling said nozzles, and a rotary unit

comprising a fan and buckets, the latter arranged in relation to be impinged by the jets from the nozzles.

5. In a turbine blower, the combination of a support, an annular steam chest carried thereby, branches extending outward from said steam chest, forwardly inclined nozzles connected to said branches, individual cut-off valves therefor, and a rotary unit in front of said steam chest comprising a fan and buckets, the latter arranged in relation to be impinged by the jets from the nozzles.
- 10 6. In a turbine blower, the combination of a support, an annular steam chest carried

thereby and provided with nozzle branches, 15 nozzles connected to said branches, said nozzles being arranged tangentially and inclined forward, cut-off valves controlling said branches and having stems extending rearward and accessible at the back, and a 20 rotor comprising fan blades and buckets in front of said nozzles.

ALBERT L. WOLFSON,
ALFRED N. HAMMERSTON.

In presence of—

MAURICE HOTCHNER,
CLARENCE G. GALSTON.
